[57] ABSTRACT

A floating body is anchored by plural anchor chains having means for limiting the tension therein. Each chain runs through an eye of the anchor to a completely and permanently submerged float so that when a predetermined maximum tension is reached, the chain is drawn through the eye and the float sinks further in the water. A stop on the chain between the anchor and the anchored body limits the height to which the submerged float can rise in the water.

ARRANGEMENT FOR ANCHORING A FLOATING BODY

The invention relates to an arrangement for anchoring a floating body and which comprises two or more anchor chains extending therebelow and anchored in or to the sea-bed. Such an anchoring arrangement is generally known, and an example thereof is a ship moored fore and aft by anchors or a buoy having a number of anchors set out therearound. If one wants to maintain the floating body in a more accurate position the anchor chains can be initially tensioned accordingly. The elasticity of the anchoring arrangement and the movability of the floating body therethrough is dependent on the weight and the form of the anchor chain or chains, which movability is decreased with the tightening of a chain or chains. Too great a tightening in a chain or chains results in breakage thereof.

For buoys and floating islands, it is of the greatest importance that they should be anchored accurately in their places of operation in consideration of respectively, the lines connected thereto, or the work which is to be executed therefrom such as offshore drilling whilst, on the other hand, under no circumstance must the anchor chains break.

The present invention aims at providing a simple solution to this problem, and this aim is achieved according to the present invention in that a number or all of the chains are each fed through a guide-member of the anchor particular thereto, and past the guide member coupled to a permanently and completely submerged float, each of which chains being provided with a stop thereon on the side thereof adjacent the body to be anchored, and each of which stops cannot pass the guide-member. Through this measure, and by the correct choice of float, it is possible for the chains to be pulled through the guide-member when a certain tension in the chain, below the breaking-strain, is reached and whereby the float is pulled deeper into the water, and such that a more constant tension in the chain results. Should then the initial tension in one, or more, of the chains be exceeded the float(s) then exercise their function such that the tension in the concerned chain, or chains, is maintained constant. The tension in a chain at which the float particular thereto exercises its function can be higher than the initial tension, but it must also be below the limit at which the danger of breakage of the chain begins.

It is known to anchor a ship by a cable which is coupled, via a return sheave on the sea-bed, to a float at sea-level, which float constantly functions to exercise a varying anchoring force which is dependent on the degree to which the float is submerged. This system is disadvantageous, in particular when movement of the ship and float are out of phase since then suddenly large forces manifest themselves in the cable.

The present invention will be understood from the following description read with reference to the accompanying drawings in which:

FIG. 1 schematically illustrates an anchoring arrangement according to the invention, and

FIGS. 2 and 3 are force/displacement diagrams.

Referring in the first instance to FIG. 1, a mooring buoy 1 is provided with a turn-table 1a for the mooring thereto of a tanker, or ship (now shown). The buoy 1 is anchored to the sea-bed with the aid of anchor chains 2. Only two chains are illustrated in the drawings al-

though more chains can be employed and which extend in different directions. In the known anchoring arrangement the anchor chains extend to anchors in the form of, for example, concrete blocks. In FIG. 1 anchor chains 3 are shown which extend into the sea-bed although any type of anchor is employable with the provision that it is equipped with a guide-eye 4 through which an anchor chain 2 can run. Each of the chains 2 is provided with a stop 5 thereon, and with the portion 10 2 a thereof, passed through the guide-eye 4, coupled to a float 6 which is in a submerged condition.

The chains 2 hang with a certain initial tension therein. Should the chains be displaced to assume the positions illustrated by the chain-dotted lines, then the 15 most heavily loaded one thereof will, on reaching a certain predetermined tension therein, exert a pull on the float particular thereto such that the tension in the chain will not increase.

FIG. 2 shows a diagram in which the displacement of 20 a fore-and-aft anchored body is indicated along the horizontal axis of the graph and in which the corresponding anchoring forces are indicated along the vertical axis thereof. The relationship between displacement and corresponding anchoring forces is given by 25 the curve 10.

If a ship is subjected to a force P1 then its displacement will be from O to A1, and the energy taken up in anchoring is indicated by the hatched area 11.

As the result of the attendant and changing forces the 30 ship will be displaced to and fro between, for example, points A2 and A3; and such that, in principle, the energy taken up is equal to the energy expended (represented by the hatched areas 12 and 13 of FIG. 2).

Should a pull on a chain, corresponding to the anchoring force P2, become too high then the pull in the chain will be limited by the pulling of the float downward thereby.

In principle, the diagram of FIG. 3 is the same as the 40 diagram of FIG. 2. It illustrates however, what occurs when the predetermined limit of tension in a chain is reached through the application of the force P3, when the float is activated to perform its function. The force P3 then remains constant over the whole range of permitted displacement of the float 6.

As clearly shown in the diagram, it has been found 45 that the energy which can now be taken up is considerably greater and such that the anchoring arrangement can stand heavier anchoring conditions, and higher initial tensions can be applied to the same chains.

What we claim is:

1. An arrangement for anchoring a floating body, comprising a plurality of anchor chains secured to and extending below the floating body, a plurality of anchors on the sea bed, each anchor having a guide member through which a said anchor chain slidably extends, a permanently and completely submerged float on the end of each anchor chain remote from the floating body, each said chain having a stop thereon between the floating body and the anchor which stop is closer to the associated said float than to said floating body so as to maintain said float permanently and completely submerged and said stop cannot pass through said guide member, the distance between each stop and its associated said floating body being such that the floating body remains floating on the surface of the water when any said stop engages its associated said anchor, the length of said anchor chain between each said stop

and said floating body being substantially greater than the vertical distance between any said anchor and said floating body.

2. An arrangement as claimed in claim 1, the length of each said anchor chain being such that when any said float contacts its associated said anchor, a said stop of another said anchor chain will contact its associated

said anchor.

3. An arrangement as claimed in claim 2, the lengths of said chains being such that said another anchor chain lies slack on the sea bed to a substantial distance from its said associated anchor.
